UNITED STATES PATENT OFFICE.

EDWARD VARNER, OF ROCHESTER, NEW YORK, ASSIGNOR OF ONE-THIRD TO FRANK E. MEHLE AND ONE-THIRD TO JOHN A. STAPLETON, BOTH OF ROCHESTER, NEW YORK.

CAR HEATING AND VENTILATING SYSTEM.

1,139,089.

Specification of Letters Patent.

Patented May 11, 1915.

Application filed February 1, 1912. Serial No. 674,719.

To all whom it may concern:

Be it known that I, EDWARD VARNER, of Rochester, in the county of Monroe and State of New York, have invented a new and useful Improvement in Car Heating and Ventilating Systems, which improvement is fully set forth in the following specification and shown in the accompanying drawings.

- 10 The present invention relates to car heating and ventilating systems and an object thereof is to provide a heating system in which a train of cars may be effectively heated from one end to the other while at 15 the same time permitting the occupants of each seat to control the heat in proximity to such seat, so that the individual requirements of the passengers may be met without inconveniencing the other passengers, 20 provision being also made for ventilating the car in proximity to each seat with a means which is also subject to the control of the occupants of such seat.

To these and other ends the invention 25 consists in certain parts and combination of parts all of which will be hereinafter described, the novel features being pointed out in the appended claims.

In the drawings: Figure 1 is an enlarged 30 interior view of a portion of a passenger car showing the position of the heating and ventilating units relative to the car seats; Fig. 2 is an enlarged view of the piping, illustrating the controlling valve; Fig. 3 is a sectional view showing the controlling valves adjusted as to deliver steam from one car to the one adjacent thereto; Fig. 4 is an enlarged view of the combined heating and 35 ventilating unit employed in connection with the system, the open work front wall of the unit being removed; Fig. 5 is a vertical section on the line *a—a* Fig. 4; Fig. 6 is a horizontal section on the line *b—b* Fig. 4; and Fig. 7 is a vertical section through 40 the combined heating and ventilating unit.

According to the illustrated embodiment 45 of the invention, each car preferably has a feed pipe 5^a and a return pipe 3^b arranged on the under side thereof, and coupling devices of known construction (not shown) are adapted to attachably connect the feed and return pipes of connected cars.

To the end that each car may serve as the rear car of the train without affecting the 50 operation of the heating system, each car is

preferably provided near each end with a bypass or connection 7 which is adapted to connect the feed pipe 5^a on any one car with its return pipe 3^b. Preferably this connection is located on the inner side of two 60 valves 8 and 9 which are provided respectively in the pipes or connections 3^b and 5^a for the purpose of closing such pipes at the ends of the car. The connection 7 may also have a valve 10 which closes the pipes 3^b 65 and 5^a against communication when the valves 8 and 9 are open. Preferably a single operating member is employed for simultaneously controlling the valves 8, 9 and 10. In this instance, a lever 11 pivoted at 12 to 70 the car body has a slotted end 13 operating upon a projection 14 provided on a valve operating crank 15, said crank being connected by links 16 and 17 respectively to cranks 18 and 19 on valves 8 and 10 respectively. 75

Within each car and preferably countersunk into the side wall thereof between the seats A are located the combined heating and ventilating units. The construction of 80 these units will be set forth hereinafter, only the heating member or radiator being at this time referred to and preferably comprising a coil of piping 20, one end of which is connected by a piping 21 to the feed pipe 5^a while the other end is connected by a piping 22 to the return pipe 3^b. A valve 23 may control the inlet to the radiator while a valve 24 controls the outlet. It will thus be apparent that the radiators are connected 85 in parallel so that the condition of one radiator does not affect the other radiators. In this way, the temperature in proximity to one seat may be varied without materially affecting the temperature of the remaining portions of the car. 90 95

According to the present embodiment of the invention, the radiators 20 are each housed within a chamber 25 preferably formed within a casing 26. The front wall 100 of said chamber is an open work or reticulated plate 27 which is substantially flush with the inner face of the side of the car, whereas the rear wall of the chamber 25 is formed by a partition 29 of cork or other 105 suitable material which will act to deaden the sound between the wheels and the interior of the car. The interior faces of the chamber 25 are preferably covered with asbestos or other heat non-conducting sub- 110

stance, and air is admitted to the chamber 25 by way of openings 30 leading into the chamber 31 in rear of the chamber 25 and having screens 32 thereover for excluding 5 dust from the chamber 25 and consequently from the interior of the car.

The chamber 31 has two openings 33 which are located at the bottom of the car and partially inclosed by hoods 34, said 10 hoods projecting below the car bottom and opening in opposite directions, so that, during the travel of the car, the hood opening in the direction of said travel may be employed for directing air into the chamber 31 15 and, by way of the ports or openings 30, to the radiator chamber 25 where it is heated and delivered to the car. Preferably when one hood is open the other is closed for otherwise the latter would tend to suck the 20 air from the chamber 31. To this end, valves 35 may be employed preferably in the form of plates hinged at 36 within the hood and adapted to swing to close the openings 33, the hoods thus serving to limit the movements 25 of the valves. The controlling means for said valves comprises preferably links 37 each hinged at 38 to one of the valves 35 and also hinged at 39 to one arm of a bell-crank lever 40 which is pivoted at 41 and 30 extends upwardly through the casing 26 where it carries a locking device in the form of a slide bolt 42 for coöperation with a rack 43. The top wall of the casing 26 lies in a plane with the window sills of the car and 35 forms portions of two adjacent window sills in that type of car where two windows separated by a stile are provided between two facing seats as in the ordinary "Pullman car". In this way, the operating portions 40 of the valve controlling mechanisms are readily accessible to the occupants of the seats without interfering with the use of the window sills as arm rests. The operating stems or members 44 of the valves 23 and 24 45 also have hand pieces 45 arranged above the casing 26 so as to be readily accessible.

The ventilation of the car is preferably effected by drawing air through side walls of the car near the bottom and between the 50 members of each pair of facing seats so that the ventilation may be easily controlled by the occupants of such seats without materially affecting the condition of the air in proximity to the other seats. In the present 55 instance, each of the casings 26 is provided with an ejector chamber 46 having a screened outlet 47 on the outside wall of the car. The air to said chamber is admitted by way of oppositely opening inlets 48 having dust 60 screens at their lower ends and merging into each other at the bottom of the chamber 46, the air therefrom being directed upon a rotary bladed wheel or fan 49, the air hitting such wheel in a direction to cause the rotation 65 thereof before passing through the

screened outlet 47. This causes a suction through the exhaust passage 50 opening into the car, said exhaust passage being covered by the screen 27 which is extended downwardly from in front of the radiator 20. 70 The purpose of the fan is to equalize the suction through the exhaust 50 as otherwise the air entering the chamber 46 from the oppositely opening inlets 48 would pass through the chamber 46 differently for the 75 different directions of travel of the car and not produce a proper suction through the passage 50.

For the purpose of closing the ventilator, a valve is provided having a portion 51 for 80 closing the exhaust opening and a portion 52 for closing both of the inlets 48, said valve being slidably arranged within the chamber 46 on guides 53 and 54 and having an operating portion 55 extending into the car 85 through a slot 56.

In the use of the invention, the cars are coupled together in the usual manner, the flexible couplings of proximate cars being united, that is, the feed pipe on one car is 90 joined to the feed pipe on another car, and the return pipes being likewise connected. The lever 11 at the rear end of the rear car is turned to close the valves 8 and 9 and open the valve 10 so as to make connection 95 between the feed pipe and return pipe, whereas levers 11 at other points on the train are shifted to control their respective valves 8, 9 and 10. Steam will then pass from one end of the train to the other and 100 return to the boiler, thus making a complete circuit. Any radiator on the train may receive steam from this circuit by opening its valves 23 and 24. The valves 35 for supplying air to the radiators are adjusted so 105 that the hoods 34 opening in the direction of travel of the train will supply air while the other hoods will be closed, the adjustment being determined by the passengers occupying the seats in proximity to such radiator. For opening or closing the ventilators, the hand pieces 55 are employed. 110

An important result secured by the present invention is that the individual passenger may control both the heating and the 115 ventilation of the car in proximity to his seat. It is well known, that rail-road employees have a great deal of difficulty in heating and ventilating a car to suit everybody within the car. This invention enables each passenger to get as much heat or as much air as desired without materially affecting the remaining portion of the car. 120

What I claim as my invention and desire 125 to secure by Letters Patent is:

1. In combination with a car having a plurality of seats within the same, and air chambers formed in the side walls of the car between the seats and each provided with oppositely opening inlets in its bot- 130

tom leading to the exterior of the car and an outlet leading to the interior of the car, feed and return steam pipes on the car, radiators arranged in the chambers and connected in parallel with the feed and return pipes, independent valves on the radiators permitting any one or more to be closed independently of the others, and means for closing either or both of the inlets of each 10 air chamber independently of the other chambers.

2. In combination with a car having a plurality of seats within the same and air chambers in the vertical walls of the car 15 between the seats, feed and return steam pipes carried by the car, radiators arranged within the air chambers and connected in parallel to the feed and return steam pipes, independent valves for the radiators permitting any one or more to be closed independently of the others, and independent 20 valves for the air chambers permitting any one or more to be opened or closed independently of the other chambers.

25 3. In combination with a car having a plurality of seats within the same and air chambers in the vertical walls of the car between the seats, feed and return steam pipes carried by the car, radiators arranged 30 within the air chambers and connected in parallel to the feed and return steam pipes,

independent valves for the radiators permitting any one or more to be closed independently of the others, independent valves for the air chambers permitting any one or 35 more to be opened or closed independently of the other chambers, and a controllable outlet from the car adjacent to each air chamber.

4. In combination with a car having a plurality of seats within the same, and air chambers formed in the side walls between the seats and each provided with oppositely opening inlets positioned on the bottom of the car and leading to said chamber, and an outlet leading to the interior of the car, feed and return steam pipes on the car, radiators arranged in the chambers and connected in parallel with the feed and return pipes, independent valves on the radiators 50 permitting any one or more to be closed independently of the others, means for closing either or both of the inlets of each air chamber independently of the other chambers, and controllable outlets leading 55 through the side walls of the cars between the two inlets of each chamber.

EDWARD VARNER.
